[57] CLAIM

The ornamental design for a powered soil working tool, as shown and described.

DESCRIPTION

FIG. 1 is a left, side elevational view of a powered soil working tool showing my new design;

FIG. 2 is a front elevational view thereof;

FIG. 3 is a rear elevational view thereof;

FIG. 4 is a top plan view thereof taken substantially along line 4—4 of FIG. 1;

FIG. 5 is a bottom plan view thereof;

FIG. 6 is a left, side elevational view of a powered soil working tool showing a second embodiment of my new design;

FIG. 7 is a front elevational view of FIG. 6;

FIG. 8 is a rear elevational view of FIG. 6; and

FIG. 9 is a bottom plan view of FIG. 6.

Fig. 3.

Fig. 5.

Fig. 4.
